UNITED STATES PATENT OFFICE.

ASGER EILERSGAARD, OF CHICAGO, ILLINOIS, ASSIGNOR TO LINK-BELT COMPANY, OF CHICAGO, ILLINOIS, A CORPORATION OF ILLINOIS.

CLAM-SHELL EXCAVATOR.

1,269,802.

Specification of Letters Patent. Patented June 18, 1918.

Application filed December 23, 1915. Serial No. 68,320.

To all whom it may concern:

Be it known that I, AASGER EILERSGAARD, (who was a subject of the King of Denmark, but who has made application for 5 American citizenship, but not yet completed the formalities of becoming an American citizen,) residing at Chicago, in the county of Cook and State of Illinois, have invented a certain new and useful Improvement in 10 Clam-Shell Excavators, of which the following is a specification.

My invention relates to improvements in clam shell buckets, and has for one object to provide bucket closing means which will 15 give great closing power without a disproportionate resistance to opening. Another object is to provide a chain bucket which will have an increased closing power where- 20 in the closing force will not decrease un- duly as the bucket approaches the closed condition. Another object is to provide a differential chain closing mechanism for a clam shell bucket. Another object is to 25 provide means for drawing in a part of the closing chain means for paying out another part to compensate for the change in the radius arm through which the closing force is applied. Other objects will appear 30 in the specification. My invention is illus- trated more or less diagrammatically in the accompanying drawings, wherein—

Figure 1 is an end elevation;

Fig. 2 is a side elevation;

Fig. 3 is a side elevation showing the 35 bucket open;

Fig. 4 is a section along the line 4—4 of Fig. 3;

Fig. 5 is a section along the line 5—5 of Fig. 4;

Fig. 6 is a section along the line 6—6 of Fig. 4;

Figs. 7, 8, 9 and 10 show diagrammatically the position of the closing chains and closing cams and associate parts at the open 45 position, at two partially closed positions, and at the fully closed position.

Fig. 11 is a detail end elevation of a slightly modified form showing some of the parts in the closed position with the clos- 50 ing chains removed.

Fig. 12 is an end elevation of modified form of scraper bucket with my device applied thereto.

Fig. 13 is a side elevation of Fig. 12;

Fig. 14 is a side elevation of the modified

form showing the buckets in the open posi- tion.

Fig. 15 is a section along the line 15—15 of Fig. 14.

Like parts are indicated by like letters 60 in all the figures.

Referring first to the preferred form shown in Figs. 1 to 11, A, A¹, are bucket jaws. They have upwardly projecting from them the arms A², A³, pivotally tied 65 together by the pin A⁴. A⁵, A⁶ are built up shear legs pivoted respectively on the outer upper edges of the buckets A, A¹ and pivoted together on the yoke A⁷.

B is a drum rotatably mounted on the pin A⁴. About this drum is wound a cable B¹, which cable passes up over the sheave B² on the yoke A⁷ to a suitable source of power. B³ is a hub integral with the leg A² and rotatably mounted on the pin A⁴. 75 On this hub is keyed a segment B⁴. B⁵ is a cam integral with the drum B and mounted to rotate with it upon the pin A⁴. B⁶ is a cover of guard about the lower portion of the drum B. It is mounted on and integral with the segment B⁴. 80

C is a hub rotatably mounted on the arms C¹ downwardly projecting from the yoke A⁷. C² is a cam on one side of the hub immediately above the segment B⁴. C³ is a 85 cam on the other side of the hub immediately above the cam B⁵. C⁴ is a cam controlling chain. It is anchored at one end on the lower extremity of the segment B⁴ and at the other end on the outer extremity 90 of the cam C². C⁵ is the closing chain. It is anchored at its lower extremity at the innermost point of the cam B⁵, and at its upper extremity on the outermost point of the cam C³. The arrangement of cams and 95 chains is such that when in the open position the cam controlling chain is wound almost entirely off the segment and off the cam C², and the closing chain is anchored on but wound off the cam B⁵ but wound 100 clear around the cam C³, so that substantially a full revolution of that cam will be required to pay off the closing chain.

In the modified form shown in Figs. 12 to 15, the bucket members D, D¹, are provided with long upwardly extending arms D², D³, pivoted on a T-shaped yoke, D⁴ the central arm of the T extending downwardly to a point approximately intermediate the upper outer edges of the bucket members. 110

D⁵ is a hoisting line attached to a yoke D⁶. The yoke carries sheaves D⁷, D⁸, and supports the chains D⁸, D⁹, which chains are pivoted at their lower upper ends on horns D¹⁰, D¹¹, on the arms D², D³.

E is a closing drum. E¹ is a closing cable wound about it, which cable leads up between the sheaves D⁷ to a suitable power source. It will be noted that instead of having as in the preferred form one closing and one controlling chain, I provide two. This is necessitated by the fact that in this modified form it is necessary to draw each of the bucket or scraping members in toward the center, whereas in the previous form it was only necessary to draw the central pivot connection between the two buckets, upwardly toward the apex of the shear frame. Aside from this difference the operation is exactly the same. Certain changes in detail, however, are necessitated. The cam arrangement on each of the arms D², D³, is exactly the same as the cam arrangement on the yoke C¹. The winding drum, however, has integral therewith on either side thereof the spools E². Upon these spools are adapted to be wound the closing chains. The controlling chains are provided with stirrup or link connections E⁴, which are pivoted on the pin E⁵ tying the parts together.

It will be evident that while I have shown in my drawings an operative device, still many changes might be made in size, shape and arrangement of parts without departing from the spirit of my invention.

The use and operation of my invention are as follows:

Referring first to the preferred form with the parts in the position shown in Fig. 3, it will be understood that the arrangement of the chains and cams is that shown in Fig. 7, the upper cams being integral and rotatably mounted on their pivoted pin, are free to turn. The operator commences to draw in on the hoisting cable. This cable at the start is wound three times about the hoisting drum. It will be noted that the point at which the controlling chain is attached to the cam on the drum is about twenty degrees below the horizontal. One revolution of the hoisting drum will draw in the hoisting cable one revolution, and this will pull the upper cam about which the chain is wound over through approximately ninety degrees as indicated. The controlling chain will at that time commence to be wound up on its upper cam. The closing movement of jaws having commenced the segment upon which the lower end of the controlling chain is anchored, will travel down through approximately thirty degrees. The next complete rotation of the hoisting drum will wind the hoisting chain once more about it.

65 The chain is a flat one, and as the movement

continues, will wind about itself on the drum or cam. The lever arm is thus increased and the closing force exerted decreased, but by this time the upper cam about which the closing chain is wound, will have rotated to decrease that lever arm, and thus counterbalance the increase caused by the increase of the lower lever arm. This rotation of the cam is permitted by the approach of the two axes. Meanwhile, however, the controlling chain will have been drawn in about seventy degrees. Thus the upper cam about which the closing chain is wound, will not pay out that chain quite as rapidly as would be the case if the rotation of the cam were controlled by the approach of the two axes of rotation. The next revolution pays out all the cable on the drum, winds up all the closing cable and leaves the parts in the position shown in Figs. 10, 1 85 and 2. The chain by that time will have been completely paid out from the upper cam and the controlling chain will have been drawn down about the lower shaft to the full length of the segment and up about 90 the upper shaft upon the cam. Thus it will be observed that the cam arrangement, as shown causes the increase in lever arm through which the closing force works on the drum shaft to be counterbalanced by a 95 decrease in the lever arm through which the controlling chain works, and an increase of the lever arm through which the closing chain works on the upper shaft, thus the turning moment available as a result of the 100 tension in the cable is at all times the same independent of the number of coils of chain about the windlass or housing drum shaft.

The operation is exactly the same in the case of the modified form, the only difference being that there are two sets of closing and controlling chains at work, each set tending to pull its own bucket toward the center line.

Thus the arrangement is to a large extent 110 productive of a differential result. That is to say, while one chain is paid out another one is drawn in. The movement of one chain being greater than the other results in a gradual drawing together of the chain anchorages which gradual drawing together is not as rapid as the movement of the chain.

115 In a certain sense the two chains, that is to say, the chain which I have called the closing chain, and the chain which I have called the cam controlling chain, may be regarded as two parts of the same loop of continuous chain, that is, in a sense what happens is that the winding up of the chain about the hoisting drum hub pulls in on both lengths of chain only by virtue of the fact that the double cam arrangement is inserted between the two ends of the chain system. The result is a differential chain movement, and this differential chain move- 130

ment might obviously be obtained by some other mechanism than the double cam arrangement.

The mechanical movement which operates to close the buckets does so by drawing together two pivot axes. That is to say, the pivot axes along which the two buckets are articulated is drawn upwardly toward the pivot axis along which the two frame legs are articulated. This upward movement of the bucket pivoted axis is caused by three separate coöperating forces, one of them the upward tension in the closing cable. This tension is always the same from the beginning to the end of the closing movement. This tension or force acts through a fixed lever arm tending to rotate the power drum. It is this rotation of the power drum which operates the other two cables which I have for convenience termed the cam controlling and the closing cable, though obviously both of them are closing cables in a very true sense. These two cables and their cams are so arranged that during the closing movement the consummation of the force exerted by both of them is constant, but the force exerted by each individual cable obviously varies, and it is the varying force exerted by said cables which when compensated for results in a bucket closing mechanism which exerts a constant force at all times from the commencement to the end of the closing movement. This can best be seen in Figs. 7 to 10 which are applicable to both modifications. That is to say, the only change to make them applicable to the second type would be to duplicate the system.

We will therefore consider the one modification. In the position shown in Fig. 7 when the shaft A⁴ is rotated the chain C⁵ tends to wind about the hub B⁶ and the rotation of the hub exerts a certain predetermined tension in the chain tending to cause the shaft A⁴ to move upwardly. The tension in the chain is resisted by a tension in the chain C⁴ which tends to prevent rotation of the cam C³ by the weight of the bucket assembly, but since the rotation of the hub shortens the chain C⁶, the shaft A⁴ must perform rise. This permits the chain C⁴ to pay out and allows a rotation of the cams C², C³, so that at the end of the first revolution of the power drum the cam C² will have rotated until the chain C⁴ is wound up upon it for a short distance. This permits a rotation of the cam C³ until the chain C⁶ has wound off it slightly. The lever arm through which the chain C⁶ acts on the cam C³ is increased. The lever arm through which the hub acts on the chain C⁶ is also increased owing to one coil of chain being wound upon another. The force tending to rotate the hub is constant, so that a smaller force is available tending to pull the chain C⁶ downwardly, but this smaller force is

equalized by the longer lever arm through which that chain works, tending to rotate the cam C³ so that the tension in the chain C⁴ is now increased. This process continues as shown in Figs. 9 and 10 with the tension in the chain C⁵ decreasing proportionately at each revolution of the power drum and the tension in the chain C⁴ increasing proportionately at each revolution of the power drum until the parts have been drawn into the position shown in Fig. 10.

I have spoken above of the different lever arms available. It is understood, of course, that the reason why there is a difference in leverage is because of the fact that the chain as it is wound about the hub due to the rotation of the hoisting drum piles coil upon coil and increases the lever arm, thus decreasing the advantage of the mechanism. This increase in lever arm is compensated for as above pointed out by the coöperation of the two opposed cams. These cams are arranged so that while these wind up, in this case 83 inches of chain the travel between the head and the drum is only 54 inches. The three foot travel of chain beyond the travel of the mechanism itself is taken care of by winding the chain off one cam and winding it on another cam and it is this coöperation of these two cams and the chain sections wound about them which produces the desired result whereby 83 inches of chain travel gives 54 inches of travel of the drum with respect to the head.

I claim:

1. An excavating bucket comprising two jaws pivoted one on the other, a power drum, a cable wound a plurality of times about it, a hub integral therewith, and a chain having one end anchored thereon, a movable anchorage for the other end of the chain and means responsive to the relative angular movement of the two jaws and to the rotation of the power drum for compensating for the change in the length of the lever arm through which the chain acts, resulting from the winding of one coil of chain upon another on the hub as the cable is wound off the drum.

2. An excavating bucket comprising two jaws pivoted one on the other, a power drum, a cable wound a plurality of times about it, a hub integral therewith, and a closing chain having one end anchored thereon, a head supported above the jaws, a pair of oppositely disposed cams rotatably mounted on the head the closing chain being anchored to and adapted to wind about one of the cams, a controlling chain anchored on and adapted to wind about the other cam, said controlling chain being anchored at its free end on one of the jaws.

3. An excavating bucket comprising two

- 4
5. Jaws pivoted one on the other, a power drum, a cable wound a plurality of times about it, a hub integral therewith, and a closing chain having one end anchored thereon, a head supported above the jaws, a pair of oppositely disposed cams rotatably mounted on the head the closing chain being anchored to and adapted to wind about one of the cams, a controlling chain anchored on and adapted to wind about the other cam, said controlling chain being anchored at its free end on one of the jaws, a segment on the jaw about which said controlling chain is adapted to be wound.
15. 4. Closing means for clam shell excavators and the like comprising a power drum and means for rotating it, a hub integral with the drum, a two part closing chain having one end adapted to be wound about the hub, another end of the chain being anchored on the bucket, two cams removed from the power drum oppositely disposed and adapted to rotate in unison, the two remaining ends of said two part chain being anchored respectively one upon each of said cams.
20. 5. Closing means for clam shell excavators and the like comprising a power drum and means for rotating it, a hub integral with the drum, a two part closing chain having one end adapted to be wound about the hub, another end of the chain being anchored on the bucket, two cams removed from the power drum oppositely disposed and adapted to rotate in unison, the two remaining ends of said two part chain being anchored respectively one upon each of said cams.
25. 6. A clam shell bucket comprising two pivoted bucket members, a closing drum mounted for rotation upon their pivot axis, a chain drum mounted for rotation with the closing drum, a controlling segment mounted for rotation concentric with the closing drum upon one of said bucket members, shear legs pivoted on the bucket members and pivoted together above the bucket member pivot axis, a pair of cams mounted for rotation upon the shear leg pivot axis, said cams being oppositely disposed, a closing chain anchored on the chain drum and on one of said cams, a controlling chain anchored on the controlling segment and the other cam, a cable wound about the closing drum, the relative positions of the parts being such that when the cable is wound about the closing drum the closing chain is wound about its cam and anchored on but not wound about the chain drum, and the controlling chain is anchored on but not wound about the controlling segment and the controlling cam.
65. 7. A mechanical movement comprising a

drum and means for rotating it, a chain drum integral therewith, a controlling segment mounted for rotation upon an axis concentric therewith, a pair of opposed cams mounted for rotation about an axis removed from the axis of rotation of the drum and chains anchored one upon each of said cams at one end and upon said chain drum and controlling segment respectively at the other, the relative position of the parts being such that when one chain is wound about the chain drum it is wound off its cam and the other chain is wound upon its cam and also upon the segment.

8. An excavating bucket comprising two jaws pivoted one on the other, a head supported above them, a closing chain and a controlling chain interposed between the support and the jaws, cams oppositely disposed adjacent one end of each of said chains, the chains being anchored on the cams the opposed ends of the chains being attached one of them to a winding drum rotatably mounted the other to a segment rigid with one of the jaws, a power drum and means for rotating it to rotate the winding drum to wind the chain thereabout, the relative position of segment, winding drum and cams being such that as the rotation of the winding drum draws in on the chain it causes the head and jaws to approach rotating the jaws one on another and rotating the cams to pay out one chain and wind in the other.

9. An excavating bucket comprising a pair of pivoted jaws connected by driving arms, a head located above their pivoting point connecting arms joining the head and the jaws themselves and a hoisting drum mounted for rotation about the pivoting point of the driving arms and means for rotating it, a hub mounted for rotation with the hoisting drum, a cable adapted to be wound about such hub such cable consisting of a closing chain, a compensating device mounted on the head upon which said closing chain is anchored and a controlling chain anchored at one end on the compensating device and at the other end mounted on one of the driving arms, means responsive to the rotation of such driving arm as the bucket is closed for drawing in on the controlling cable.

10. Closing means for a clam shell bucket comprising a closing drum and means for rotating it, a compensating device removed from the closing drum, a hub mounted for rotation with the drum, a closing cable anchored at one end upon such hub and adapted to be wound about it and at the other end on the compensating device, a controlling cable mounted at one end on the compensating device, at the other end on a member adapted to rotate with the bucket as it is closed.

11. Closing means for a clam shell bucket comprising a closing drum and means for

rotating it, a compensating device removed from the closing drum, a hub mounted for rotation with the drum, a closing cable anchored at one end upon such hub and 5 adapted to be wound about it and at the other end on the compensating device, a controlling cable mounted at one end on the compensating device, at the other end on a member adapted to rotate with the bucket

as it is closed said compensating device comprising a pair of opposed cams. 10

Signed at Chicago, in the county of Cook and State of Illinois this 20th day of December, 1915.

ASGER EILERSGAARD.
